COMBINED TAIL GATE HINGE AND LATCH

Francis Reifsteck, Champaign, Ill., assignor of
one-sixth to J. Warren Kinney, Jr., Cincinnati,
Ohio, one-sixth to Jackson M. Luker, and one-
sixth to R. E. Winkelmann, Urbana, Ill.

Application November 15, 1950, Serial No. 12,995

Term of patent 14 years

(Cl. D14—6)

To all whom it may concern:

Be it known that I, Francis Reifsteck, a citizen
of the United States, residing at Champaign, in
the county of Champaign and State of Illinois,
have invented a new, original, and ornamental
Design for a Combined Tail Gate Hinge and
Latch, of which the following is a specification,
reference being had to the accompanying draw-
ings, forming part thereof.

Fig. 1 is a front elevational view of a combined
tail gate hinge and latch, showing my new design.

Fig. 2 is a side elevational view of the device
of Fig. 1.

Fig. 3 is a top plan view of the device of Fig. 1.
I claim:

The ornamental design for a combined tail gate
hinge and latch, as shown.

FRANCIS REIFSTECK.
